DRESSER VALET TRAY

Roger E. Davis, Traverse City, Mich., assignor to The Setwell Company, Traverse City, Mich., a corporation of Illinois

Filed Dec. 27, 1963, Ser. No. 77,948

Term of patent 14 years

(Cl. D33—3)

FIG. 1

FIG. 2

FIG. 3

FIG. 4

FIG. 1 is a plan view of a dresser valet tray embodying my new design;

FIG. 2 is a front elevational view thereof;

FIG. 3 is a left side elevational view thereof;

FIG. 4 is a section taken along line 4—4 of FIG. 1.

I claim:

The ornamental design for a dresser valet tray, as shown.
